FIG. 1 is a front elevational view of a table lighter, showing my new design.

FIG. 2 is a side elevational view thereof, the opposite side being substantially identical thereto;

FIG. 3 is a rear elevational view thereof;

FIG. 4 is a top plan view thereof;

FIG. 5 is a bottom plan view thereof; and

FIG. 6 is a frontal perspective view thereof.

This is a continuation-in-part of co-pending design application Ser. No. 21,803, filed Mar. 9, 1970 and abandoned.

I claim:

The ornamental design for a table lighter, substantially as shown and described.
